DENTAL SURGICAL INSTRUMENT

George A. Montelius, Minneapolis, Minn.

Application March 11, 1940, Serial No. 323,340

1 Claim. (Cl. 32—46)

My present invention relates to improvements in surgical instruments and, more particularly, to dental-surgical instruments.

The objects of this invention are, first, to provide a dental-surgical instrument having characteristics intended to facilitate and improve oral dental-surgical service technique. This instrument has been designed to facilitate surgical removal of teeth roots, impacted teeth, and pathological conditions in human jaws and surrounding tissues, to reduce surgical trauma and thereby produce and hasten the healing process so necessary in avoiding post-operative pains and complications, to shorten the period of time for completing an operation in hand, to release the operator of unnecessary stress and strain, and to permit the surgeon to divert his attention from holding the instrument and allowing him to concentrate his energies on the process of the operation.

Second, to provide a surgical instrument having a shank and cutting blade that have definite relation to each other and to certain characteristics of the instrument handle.

Third, to provide a novel handle for dental-surgical instrument that affords a solid grip with no tendency to rotate in the hand during use of the instrument, and that is substantially self-balancing in the operator's hand, thus abolishing strain and fatigue of the hand and wrist during use.

Fourth, to provide an instrument handle, the contour of which complies with anatomic requirements of the hand, and also co-operates with the laws governing the sense of touch, whereby when an operator picks up the instrument, he is instantly aware, without looking at the instrument, as to the position of the cutting blade or working part thereof.

Fifth, to provide an instrument handle having opposing gripping surfaces for the operator's hand, and which surfaces are formed by grooves and intervening ridges that substantially conform, on an enlarged scale, in shape and pattern to certain of the grooves and intervening ridges on the bulbs of the finger, the result of which offers a secure grip and a comfortable and easy feeling in holding the instrument.

Other objects of the invention will be apparent from the following description and the accompanying drawing.

To the above end, generally stated, the invention consists of the novel construction and arrangement of parts hereinafter described and defined in the claim.

In the accompanying drawing, which illustrates the invention, like characters indicate like parts throughout the several views.

Referring to the drawing:

5 Fig. 1 is a side elevation of the improved dental-surgical instrument; and

Fig. 2 is a view in elevation of the instrument shown in Fig. 1 and looking at the same in the direction of the arrow indicated in Fig. 1.

10 The improved surgical instrument includes a handle 3 having a shank 4 provided at its outer end with a blade 5. The handle 3 is tapered from its outer to its inner end. In cross-section, two diametrically opposite surfaces 6 of the handle 3
15 are on the arc of a circle having its axis at the longitudinal central axis of the handle and the intervening two surfaces 7 are flat. A series of grooves 8 and intervening ridges 9 are formed in each flat surface 7 of the handle 3 at the inner end portion thereof. These grooves 8 and ridges 9 in each series extend transversely oblique to the longitudinal axis of the handle 3. These grooves 8 are relatively wide and are curved in cross-section. A depression-like seat 10 for the
20 anterior tip of the palmar surface of the first finger of an operator is formed in each of the handle surfaces 6.

The shank 4 tapers from its inner to its outer end and is round in cross-section. This shank 4 is in angular deviation relative to the longitudinal central axis of the handle 3. The longitudinal central axes of the handle 3 and the shank 4 intersect substantially at the inner end of said handle.

35 The blade 5 has a flat face 11 and its body, between the longitudinal edges of said face, is round in cross-section. The longitudinal central axis of the blade 5 is in angular deviation relative to the longitudinal central axis of the shank 4 and extends in a reverse direction from the longitudinal central axis of the handle 3 from that of the longitudinal central axis of said shank.

40

Longitudinal cutting edges 12 are provided at the longitudinal edges of the blade 5. These cutting edges 12 extend completely around the point of said blade, as indicated at 13. The flat face 11 of the blade 5 is longitudinally concave and one of the cutting edges 12, when looking at said face, is concave and the other thereof is convex. The round back 14 of the blade 5 affords an elevator for the cutting edges 12 when the handle 3 is turned about its longitudinal central axis. It is important to note that the rounded point 13 of the blade 5 is substantially in line with the center axis of the handle 3. The back 14 of the

body 5, at its outer end, is beveled for a short distance to the point 13, as indicated at 15.

The streamline design of the improved handle gives the same an artistic and pleasing appearance and at the same time the handle is highly efficient, easy to hold without effort, and gives the operator's hand a secure and easy feeling without strain other than that in manipulating the instrument to produce its required function.

In handling the improved instrument, the operator grips the handle 3 with his thumb on one of the groups of grooves 8 and intervening ridges 9 and with his first finger on the opposing or other group thereof, and with his first finger in one of the depression-like seats 10. It will thus be seen that the operator has a secure and firm grip on the handle and due to the novel contour, there is no tendency of the handle to rotate in his hand.

As heretofore stated, the oblique grooves 8 and ridges, although on a greatly enlarged scale, substantially conform in shape and pattern to certain of the grooves and ridges on the bulbs of the finger, with the result that the operator's hand holding the instrument has a comfortable and easy feeling. Also as heretofore stated, the novel contour of the handle and the relative position of its cutting blade or other working part cooperates with the laws governing the sense of touch and thereby, when the operator picks up an instrument, he is instantly aware, without looking at the instrument, as to the position of the cutting edge or other working part. In other words, by the use of the improved instrument a habit is formed and without thought, the operator takes hold of the handle and holds the in-

strument in the correct position in which it is to be used to perform a certain work.

What I claim is:

A surgical instrument having a handle and a blade secured thereto through a shank part, said handle having oppositely disposed flat sides with a plurality of grooves in said flat sides adjacent the shank end of the handle, said grooves being disposed in inclined relation to the longitudinal central axis of the handle; the shank part being inclined in angular relation to said longitudinal central axis of the handle, said shank part being oppositely inclined in relation to said axis as are the grooves in the handle, said blade being on the end of the shank opposite the handle and in reverse angular inclination from said longitudinal central axis of the handle from that of the shank, the point of the blade being substantially in line with said longitudinal central axis obtaining a desirable balance of the instrument in the operative position in the operator's hand; said shank and blade substantially defining a plane, the blade having two longitudinally disposed cutting edges spaced apart substantially in a plane substantially perpendicular to the first noted plane, one of said edges being longitudinally convex and the other of said edges being longitudinally concave, the face of the blade being longitudinally concave, the blade and the grooves in the handle being substantially parallel permitting a proper orientation of the point and cutting edges of the blade by the feel of the handle and grooves in the operator's hand without the necessity of viewing the point and cutting edges of the blade.

GEORGE A. MONTELUS.
